US00D629388S

(12) **United States Design Patent**
Son et al.

(10) **Patent No.:** US D629,388 S
(45) **Date of Patent:** ** Dec. 21, 2010

(54) **SPEAKER**

(75) Inventors: **Chae-Joo Son**, Namyangju-si (KR);
Ji-Gwang Kim, Seoul (KR); **Jin-Wook Kim**, Kimcheon-si (KR)

(73) Assignee: **Samsung Electronics Co., Ltd.**,
Maetan-dong, Teongtong-gu, Suwon-si,
Gyeonggi-do (KR)

(**) Term: **14 Years**

(21) Appl. No.: **29/357,345**

(22) Filed: **Mar. 11, 2010**

(51) **LOC (9) Cl.** **14-01**

(52) **U.S. Cl.** **D14/214**

(58) **Field of Classification Search** D14/204,

D14/207, 209.1, 210-214, 168, 171-172,

D14/496, 498-510; 181/143-144, 147-148,

181/150-153, 157, 198-199; 381/300-303,

381/306, 332-333, 336, 345, 361-364, 386-388

See application file for complete search history.
